UNITED STATES PATENT OFFICE.

HARRY V. WELCH, OF LOS ANGELES, CALIFORNIA, ASSIGNOR TO INTERNATIONAL PRECIPITATION COMPANY, OF LOS ANGELES, CALIFORNIA, A CORPORATION OF CALIFORNIA.

MEANS FOR SUPPORTING AND INSULATING HIGH-TENSION ELECTRODES IN ELECTRICAL PRECIPITATION APPARATUS.

1,391,436.

Specification of Letters Patent. Patented Sept. 20, 1921.

Application filed January 27, 1919. Serial No. 273,829.

To all whom it may concern:

Be it known that I, HARRY V. WELCH, a citizen of the United States, residing at Los Angeles, in the county of Los Angeles and 5 State of California, have invented a new and useful Means for Supporting and Insulating High-Tension Electrodes in Electrical Precipitation Apparatus, of which the following is a specification.

10 This invention relates to means for insulating high tension electrodes in electrical precipitating apparatus and is particularly adapted for use where the gas to be treated contains material such as acid fume, carbon 15 particles, or other suspended material which is liable to collect on the insulators and reduce the insulating efficiency thereof.

The main object of the present invention is to provide means for protecting the insulators of such apparatus in such manner 20 as to prevent collection of injurious deposits thereon.

The accompanying drawings illustrate 25 embodiments of my invention, and referring thereto:

Figure 1 is a partly sectional side elevation of a precipitating apparatus provided with my invention;

Fig. 2 is a transverse section thereof on 30 line 2—2 in Fig. 1, with the right hand portion thereof broken to show the insulator in section;

Fig. 3 is a vertical section of one of the insulators with its protecting means;

35 Figs. 4 to 6, inclusive, are vertical sections of modified forms of the insulator.

Referring to Figs. 1 and 2, the precipitator therein shown comprises a casing 1 having inlet and outlet conduits 2 and 2' adapted to 40 pass the gas to be treated through said casing, said casing having also means 3 at the bottom portion thereof for collecting and removing the precipitated material. My invention is particularly applicable in connection with the precipitation of acid fumes and when so applied, the collecting and removing means 3 may consist, as shown, of funnels at the bottom of the casing 1, connected with suitable conduits 3', for drawing off the collected liquid. Suitable collecting electrodes, such as vertical plates 4, are provided within the casing 1, being, for example, hung from the top plate 1' of the

casing in planes parallel with the direction of the flow of gas through the casing. 55

The discharge electrode system of the precipitator comprises a series of rows of discharge electrodes formed, for example, as wires 5 hung from horizontal frame bars 6 mounted on a high tension frame supported 60 by insulating means as hereinafter described, said wires being tensioned by means of suitable weights 5' at their lower ends and being arranged in rows between the respective collecting electrode plates 4. 65

The high tension frame may comprise vertical bars 7, connected by upper horizontal bars 8 and 8', said bars 8 supporting members 6 aforesaid, and lower bars 9 forming a lower frame through which the respective discharge electrodes pass so as to space 70 and retain said electrodes in proper position.

The vertical bars 7 are supported at their upper ends on horizontal beams 10, mounted 75 on the insulators 11. Each insulator 11 is provided with means for maintaining a current or stream of clean gas in contact therewith and flowing in such direction as to prevent access of suspended material to the surfaces of the insulator. The form of insulator shown in Figs. 1 to 3 consist of a hollow member of insulating material, mounted at its lower end on a tubular support 12, communicating with a lateral pipe 80

13 through which clean air may be supplied to the interior of the insulator, said insulator having openings 14 through which said clean air may pass to the outside of said insulator and being provided with a hood 15, 85 mounted on top of the insulator and having a depending apron 15' extending around the same so as to deflect the air in a stream passing down around the insulator. The lower end of the apron 15' is preferably 90 formed with an inwardly projecting ridge 16 so as to provide a constricted passage between it and the tubular support 12. The insulator 11 may be of any suitable material, for example, porcelain, glass or quartz, and 100 may be of any suitable form, and the hood 15 may be of metal or other suitable material.

The insulator is preferably inclosed within an insulator box or casing 17 on top of the 105 main casing 1, said insulator box communi-

cating with the interior of the main casing 1 through vertical tubes 18 so that the suction of the gas passing through the treater will draw air or gas inwardly through pipe 13, 5 tubular support 12, insulator 11 and then down within the hood 15 and through the insulator box and the tubes 18 to the casing 1. The vertical hangers or frame bars 7 for the high tension frame pass vertically 10 through these vertical tubes 18 so that the only communication between the insulator box and the treater casing is through these tubes and the tendency of the finely divided suspended material to diffuse into the insulator box is therefore resisted and overcome 15 to a large extent by the steady flow of gas downwardly through these tubes; however, in case of acid fume, or finely divided carbon, and some other materials, the tendency 20 for diffusion is so great that some of such material will inevitably enter the insulator chambers, this being particularly the case while there is liability to fluctuation of pressure with the result that there is a tendency 25 occasionally to reversal of gas stream through the communicating tubes 18. The fact that the clean gas from outside is continually passing down around the insulator 11 from the openings 14 and within the 30 hood 15 insures that any suspended material that may enter the insulator casing or chamber will be kept away from the surfaces of the insulator, and the construction of the passage at the lower end of the hood 35 also conduces to this effect.

In order to facilitate access to the insulator in case of accident, or in the possible eventuality of its requiring cleaning from time to time, the hood 15, or a portion thereof, 40 may be made removable, as shown more particularly in Fig. 3, said hood comprising a cylindrical apron or wall 15', detachably mounted on the top plate 19, which rests on the insulator 11. Any suitable means 45 may be provided for detachably holding said cylindrical apron on the top plate, for example, swinging lugs 21 mounted on the member 15' and passing through notches 22 on the top member 19, said lugs being provided 50 with nuts 23, screwing thereon and engaging with the top plate to hold the member 15' firmly in position.

In case gases carrying acid fume are being treated, it is desirable to provide means for 55 heating the protective gas stream for the insulator and for this purpose a heater, for example, an electric heater 25, may be provided within a box 26, communicating with the inlet pipe 13 and connected to the bottom of the tubular member 12, said electric heater being supplied with electric current through suitable connections 27. This 60 heating action aids in the circulation of the gas and tends to keep the insulator body warm and dry in passing upwardly

through the same and in passing downwardly on the outside of same between the insulator body and the hood, thereby insuring the effectiveness of the insulator in cases where there is liability of deposition 70 of fume or moisture on the insulator.

In electrical precipitators operating on gases of the above described character, the introduction of the high tension lead to the high tension electrodes is somewhat of a 75 problem on account of the difficulty of insulating the same where it passes through the treater casing, as any insulation provided at such point is liable to become 80 coated with the acid fume, or conducting deposit, in such manner as to nullify its insulating effect. I provide for overcoming this difficulty by utilizing the insulator construction above set forth in such a manner as to bring in the high tension lead 85 connection through the insulator support so that the same provisions which maintain the insulator clean and effective also protect the high tension lead. For this purpose the high tension circuit wire 32 may be connected to the top 19 of the hood resting on the insulator 11 and may pass down through the insulator and through the tubular supporting member 12 thereof and laterally 90 out through a tubular member 28 extending 95 laterally from the tubular member 12 and through an insulating disk or plate 29, closing the outer end of said tubular member 28.

In order to reduce the size of the tube that is necessary to prevent jump or arcing 100 of the high tension current from the wire 32 to the tubular member 12, said wire may be covered with an insulating sheath 31.

In case the insulation is of such magnitude that it becomes of importance to eliminate side strains on the insulators, the constructions shown in Figs. 1 and 2 are of advantage in that the top beams 10 extend over the insulators and have the vertical frame bars 7 hung at their ends so that the weight 110 of the high tension system is imparted through the beams 10 directly downward on the insulators, notwithstanding the fact that the vertical bars 7 are offset from the insulators. With such a construction, it is 115 preferred to inclose the horizontal beams 10, for example, by tubular casings 33, connecting the insulator boxes 17 for the respective insulators.

The hooded insulator construction may be 120 variously modified, for example, as shown in Fig. 4. The insulator may consist of a tube or cylinder 11' of quartz, or equivalent material, mounted at its lower end on the vertical tube 12' and provided at its upper 125 end with fitting 34 on which the insulator hood 35 rests, said fitting 34 being provided with openings 36 for passage of air to the space between the insulator and the hood apron 37, which may be formed as a trun- 130

cated cone, as shown in this figure. This figure also illustrates the construction of the insulator boxes 17' in such manner that it overhangs or extends out from the main 5 casing 1 and vertical tube 12' extends downwardly through the bottom of the insulator boxes so as to communicate at 18' with the outer air. The wire 32 for conducting high tension current to the high tension system is 10 shown in this case as extending vertically through the tube 12' being connected at its upper end to the hood 35 and passing at its lower end through an insulating plate 29 at the bottom of the tube 12'. 15 Another modification is shown in Fig. 5 wherein the insulator indicated at 38, is solid, consisting, for example, of a porcelain insulator of well known type, mounted on the upper end of the air inlet tube 39 and 20 supporting the hood 40. Said air inlet tube is provided with openings 41, which communicate with a space within the hood 40 so that air passing upwardly through the inlet tube will flow downwardly through the 25 hood.

In the modification shown in Fig. 6, the insulator 43 is mounted by a spider 44 on the upper end of an air inlet tube 45 and the high tension wire 46 extends upwardly 30 through said tube and laterally between the top of the tube and the insulator 43 to connect with the hood 48.

In each of the described embodiments of the invention, the operation of the electrical 35 precipitator in usual manner involves the passage of gases containing suspended material, for example, acid fume, through the precipitator chamber 1, such gases being subjected to the action of electric fields between the discharge and collecting electrode 40 systems in such manner as to cause precipitation of suspended material on the collecting electrodes in well known manner. The operation is preferably carried out by the 45 use of a high tension unidirectional current of suitable potential difference, the wire 32 leading to the high tension system being connected to any suitable source of high tension current, for example, to a high tension 50 rectifier and the casing 1 and collecting electrodes 4 being grounded so as to complete the connection in usual manner.

Diffusion of the suspended material in the 55 gas from the main chamber 1 to the insulator boxes 17 is minimized by the constricting tubes 18 and the continual current of air forced or drawn in through the tubes 13 and 12 and their openings 14 and then passing downwardly in the hood 11 insures that any 60 suspended material that may find its way into the insulator boxes will be kept away from the insulators therein. The current of air necessary for this operation may be maintained by the draft through the precipi- 65 tator, such draft being induced by connec-

tion to a stack, or otherwise, resulting in a condition of lower pressure within the treater as compared with the outside air and therefore causing air to be drawn from the outside through tubes 13 and 12 and 70 openings 14 to the insulator chamber and then down through the sleeves or tubes 18 to the main chamber 1; if desired, however, this current of clean air may be forcibly supplied to the tube 18 by any suitable means. 75 In case of breakage of an insulator, or of other injury thereto, the same may be readily inspected and repaired by releasing the insulator shield 15' and lowering the same so as to expose the insulator. 80

What I claim is:

1. An insulator comprising a hollow body of insulating material provided at its lower end with means for admitting clean gas thereto and with outlet means at its upper end and a hood surrounding the insulator and spaced therefrom, said outlet means opening into the space within said hood for passing clean gas into said space. 85

2. An insulator comprising an insulating body having a vertical passage provided at its lower end with means for supplying gas thereto and with outlet means at its upper end whereby gas is caused to pass vertically through said insulating body and means for 95 heating said gas supplied to said passage.

3. An insulator constructed as set forth in claim 2 and comprising in addition a hood extending over and around the insulator and adapted to deflect the current of 100 gas from said outlet means at the upper end of the insulator downwardly around the insulator.

4. Insulating means for the high tension electrodes of electrical precipitating apparatus, comprising a hollow insulator, supporting means for said insulator having a passage therethrough in communication with the interior of said insulator and a source of clean gas, and a hood surrounding and spaced from said insulator and having a gas-outlet at one end, said hollow insulator having a passage connecting its interior with the space between said insulator and said hood at a point remote from said 105 gas-outlet. 110

5. Insulating means for the high tension electrodes of electrical precipitating apparatus, comprising a hollow vertical insulator, tubular supporting means for said insulator having a passage therethrough in communication at its upper end with the interior of said insulator and at the other end with a source of clean gas, and an opened-bottom hood surrounding and spaced 120 from said insulator, said hollow insulator having a passage connecting its interior with the upper portion of the space between said insulator and said hood. 125

6. An insulator for high tension electri- 130

cal apparatus, consisting of a hollow insulating body, having lateral openings, supporting means for said insulator provided with air supply connections and having a 5 passage communicating with the hollow insulator to supply air thereto, and to cause air to pass outwardly through said openings and a hood mounted on said insulator and surrounding the same to deflect the air issuing 10 from said openings downwardly around said insulator.

7. In combination with a supporting frame for the high tension electrodes in an electrical precipitating apparatus, and with 15 the inclosing casing for said electrical precipitator, a plurality of insulators mounted above said casing, horizontal beams mounted on said insulators, said casing having openings in its top and vertical tubes at 20 said openings, vertical suspension bars connected to said supporting frame for the high tension electrodes and hung from said supporting beams and extending through

said vertical tubes, and means inclosing said insulators and the horizontal beams mounted 25 ed thereon.

8. In an electrical precipitating apparatus, the combination with the inclosing casing therefor of an insulator, a hollow support mounted on said casing and supporting said insulator, frame means mounted on said insulator for supporting the high tension electrodes of the electrical precipitator and a conductor extending within said hollow support for said insulator and 30 connected to the said frame means for supplying high tension current thereto, said hollow support being provided with means for conducting clean gas thereinto and with aperture means for passing such gas around 40 the insulator.

In testimony whereof I have hereunto subscribed my name this 14th day of January, 1919.

HARRY V. WELCH.
